(57) CLAIM

The ornamental design for a finned fairing extension for motor vehicles as shown and described.

DESCRIPTION

FIG. 1 is a front perspective view of the finned fairing extension for motor vehicles;

FIG. 2 is a rear perspective view thereof;

FIG. 3 is a front view thereof;

FIG. 4 is a rear view thereof;

FIG. 5 is a first side view thereof;

FIG. 6 is a second side view thereof;

FIG. 7 is a rear perspective view thereof;

FIG. 8 is a lower side perspective view thereof;

FIG. 9 is a front perspective view of the finned fairing extension engaged on a motor vehicle;

FIG. 10 is a front view of the finned fairing extension engaged on a motor vehicle;

FIG. 11 is a rear perspective view of the finned fairing extension engaged on a motor vehicle; and,

FIG. 12 is a side view of the finned fairing extension engaged on a motor vehicle.

The broken lines in FIGS. 1-8 illustrate portions of the finned fairing extension for motor vehicles which form no part of the claimed design. The broken lines in FIGS. 9-12 illustrate the environment in which the design is embodied and form no part of the claimed design.
